UNITED STATES PATENT OFFICE.

THOMAS E. FARMER, OF STOCKETT, MONTANA, ASSIGNOR OF ONE-HALF TO ITALO CHELOTTI, OF STOCKETT, MONTANA.

CURTAIN HOLDER.

Application filed April 6, 1923. Serial No. 630,275.

To all whom it may concern:

Be it known that I, THOMAS E. FARMER, a citizen of the United States, residing at Stockett, in the county of Cascade and State of Montana, have invented certain new and useful Improvements in Curtain Holders; and I do hereby declare the following to be a full, clear, and exact description of the invention, such as will enable others skilled in the art to which it appertains to make and use the same.

This invention provides a window fixture for supporting a shade roller and curtain pole in a manner to admit of the shade roller and curtain pole being swung away from the window so that access may be readily had to the window for cleaning or other required purpose, the fixture being such as to admit of the shade roller and curtain pole being readily returned to normal position and made secure.

The invention furthermore provides a fixture which may be easily and quickly placed in position or detached from the window as occasion may require, said fixture being adjustable whereby it may be adapted to different sized windows with the greatest ease and facility.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a front view of a window provided with a shade roller and curtain pole holder embodying the invention,

Figure 2 is a side view, the pivoted arm being swung outwardly from the window,

Figure 3 is a top view,

Figure 4 is a section on the line 4—4 of Figure 2,

Figure 5 is a section on the line 5—5 of Figure 2,

Figure 6 is a detail perspective view of the outer end of the pivoted arm.

Corresponding and like parts are referred to in the following description and designat-

nated in the several views of the drawings by like reference characters.

The fixture embodies two similar or like parts, the one being right and the other left and each of the parts comprises a bar 1 or like member adapted to occupy a vertical position when in place. A clamp is provided at each end of the bar 1 for attaching it to the casement 2 or trimming of a window and these clamps are adjustable 60 whereby to adapt the fixture to window casements or trimmings of different widths. Each of the clamps embodies a fixed section 3 and an adjustable section 4, the fixed section being attached to the bar 1 and projecting laterally therefrom and provided at its outer end with a toothed jaw 5 for positively engaging an edge or side of the casement or trimming. The section 4 is adjustably secured to the section 3 and is provided at its outer end with a clamp screw 6 provided at its inner end with a follower 7 to clampingly engage the opposite edge or side of the window casement or trimming 2. The section 3 may form a part of the 70 bar 1 or be separate from and attached to the bar.

An arm 8 is pivoted at its lower end to the bar 1 as indicated at 9 and its upper portion is laterally offset. The upper portion of the arm 8 is bent to extend forwardly thence upwardly, a notch 10 being formed in the extremity to receive a curtain pole 11 which is prevented from displacement by means of a catch 12 extending across the 80 open side of the notch 10 and engaging the portion of the arm bordering thereon. A bridle 13 limits the outward movement of the arm 8 and is attached at one end to the bar 1 and at its opposite end to the arm. 90 A clip 14 provided near the upper end of the bar 1 receives a clamp screw 15 which engages the arm 8 and clamps the same against a side of the bar 1 and holds it in normal or upright position. A bar 16 is 100 pivoted to the upper portion of the arm 8 and the inner ends of the bars 16 overlap and are made secure in the adjusted position by means of a clamp 17.

As hereinbefore stated, the fixture comprises supplemental parts, each being clamped to a side of the window casement or trimming, the swinging ends of the pivoted arms being connected by means of the bars 16 and clamps 17. The shade roller 18 110

is fitted to the upper ends of the pivoted arms and the curtain pole 11 is secured in the terminal notches 10. When it is required to have unobstructed access to the window, the pivoted arms 8 are released and swung outward, as indicated in Figure 2, and after the window has been cleaned or received other attention, the arms 8 are swung back into normal position and made 10 secure by the fastening means such as the clips 14 and clamp screws 15 in the manner herein indicated.

What is claimed is:

1. A curtain fixture of the character specified, consisting of a bar, attaching clamps therefor engageable with a window frame disposed adjacent opposite ends thereof and at right angles thereto, each clamp having one of its sections as an integral part of 15 said bar, a curtain supporting arm pivoted for swinging movement relatively to said bar, and means to normally hold said arm in operative position and against pivotal movement relatively to the bar consisting 20 of a clip carried by the bar intermediate said clamps and having a clamp element engageable with the arm, and means connected to the clip and to the arm to limit the pivotal movement of the latter.
- 25 2. A curtain fixture of the class described

consisting of a bar, clamp means to secure the same to a window frame in place, a curtain supporting arm pivoted to the bar, said arm above the bar being laterally offset and terminating in curtain-holding means, means 35 to secure the arm to the bar against pivotal movement, and a flexible element secured to said means and to the offset portion of the bar to limit the pivotal movement of the latter.

3. A window fixture comprising a pair of bars provided at opposite ends with adjustable clamps, arms pivoted at their lower ends to the lower ends of said bars and having their upper portions laterally offset and 40 their upper ends bent forwardly and upwardly and provided in their upper ends with curtain pole receiving notches, a bridle between each of the bars and the arms pivoted thereto, means on the bars for securing the pivoted arms in normal position, and means adjustably connecting the swinging ends of the arms to prevent relative lateral displacement thereof.

In testimony whereof I affix my signature in presence of two witnesses.

THOMAS E. FARMER.

Witnesses:

JOE CHELOTTI,
GEORGE S. LEUCHAN.
